(57) **CLAIM**

The ornamental design for a pet harness, as shown and described.

DESCRIPTION

FIG. 1 is a perspective of a pet harness according to my new design.

FIG. 2 is a perspective view of the claimed design in FIG. 1, but unattached from the pet.

FIG. 3 is a left side elevational view thereof.

FIG. 4 is a right side elevational view thereof.

FIG. 5 is a bottom plan view thereof; and,

FIG. 6 is a top plan view thereof.

The pet depicted in broken lines in FIGS. 1 through 6 illustrate environmental matter, and form no part of the claimed design.

The cross-hatching that occurs intermittently on the surfaces of the claimed design represents woven fabric, and is understood to extend across the entirety of the surface upon which it occurs.
